UNITED STATES PATENT OFFICE

PHILIP BERGMANN, OF PHILADELPHIA, PENNSYLVANIA, ASSIGNOR TO COLUMBIA STEEL EQUIPMENT COMPANY, OF PHILADELPHIA, PENNSYLVANIA, A CORPORATION OF PENNSYLVANIA

POSTING TRAY

Application filed September 17, 1927. Serial No. 220,171.

This invention relates to office appliances and in particular to posting trays of the type used by banks and other business establishments or containing the account cards or 5 sheets.

An object of the invention is to provide a posting tray with an adjustable back which may be locked in a plurality of positions.

Another object is to provide a slidably 10 mounted adjustable back for posting trays, wherein means are included for locking the back either in a vertical or inclined position.

Another object is to produce an efficient, strong and durable posting tray which may 15 be economically constructed.

Other objects and advantages will herein-after appear.

The views of the drawings are:—

Figure 1 is a side elevation of a posting 20 tray constructed according to my invention;

Fig. 2 is a vertical transverse section as seen from the line 2—2 of Fig. 1, showing a portion of the adjustable back;

Fig. 3 is a vertical section as seen from the 25 line 3—3 of Fig. 2, the back being shown in tilted position;

Fig. 4 is a view similar to Fig. 3 showing the back vertical;

Fig. 5 is a horizontal section as seen from 30 the line 5—5 of Fig. 2;

Fig. 6 is a horizontal section as seen from the line 6—6 of Fig. 2;

Fig. 7 is a similar view as seen from the line 7—7 of Fig. 2; and

35 Figs. 8 to 14 inclusive are detail perspectives of some of the parts used in constructing the back.

The device has a bottom 1, ends 2 and 3, a rigid side 4, and another side 5. These parts 40 may be formed from pieces of sheet metal, stamped into the desired form, and welded together.

The sides and ends are of equal height, but the side 5 is so formed that it can be moved 45 from a vertical position and slid into a pocket 6 formed beneath the bottom 1.

When the side 5 is in the position under the bottom (see Fig. 1) a secondary side 7, of less height than the side 5 but extending 50 the length of the tray and fixed to the ends

thereof, will prevent the sheets of paper or cards A from sliding laterally therefrom.

Each of the ends has a handle 8 pivotally mounted thereon.

The bottom 1 has feet 9 fixed at each corner, and these feet may be provided with resilient pads 10, as is customary in devices of this nature. 55

At the end 2 of the tray there is a tilttable back 11, of any approved construction. 60

Suitably supported above the bottom 1 is another bottom 12 composed of two sheets of metal extending the length of the tray, but spaced apart. 65

In the space between the two spaced parts of the bottom 12 there is a channel 13, the bottom of which rests on the bottom 1, being attached thereto by welding, or in any other suitable manner. 70

The sides of the channel 13 terminate in 75 inturned flanges 14 which are disposed in substantially the same plane as is the bottom 12.

The channel 13 is positioned lengthwise of the tray and its bottom has the central portion for its entire length formed with upstruck, inclined protuberances 15. These protuberances provide a serrated surface, the purpose of which will be hereinafter apparent. 75

Above the protuberances 15, there is a rod 16 extending the length of the tray and supported by the ends 2 and 3 thereof. 80

The tray is provided with a slidably mounted and vertically adjustable back 17. 85

The back 17 is made from sheet metal and its upper edge is formed with a bead 18.

Fixed to the rear of the back 17 is a channel member 19 in which is disposed a spring-pressed latch 20, the lower end of which engages the protuberances 15 to lock the back 90 in position.

The channel member 19 has a plurality of outstruck portions 40 which are welded to the back 17. The outstruck portions serve as means for spacing the channel 19 a slight distance from the back. The flanges 19a of channel 19 have at their lower ends notches 19b forming downwardly facing shoulders 19c, as shown in Fig. 8. 95 100

The lower edge of the back 17 carries a foot, by means of an upwardly projecting ear 21, of the same which is inserted in the space between the channel member 19 and the back 5 17.

The foot is preferably formed from sheet-metal, stamped into the shape shown in Fig. 11, so as to have a bottom composed of a pair L-shaped arms 22, which are disposed in the 10 channel 13 beneath the flanges 14, the foot thus comprising a guide member.

When the back 17 is in the position illustrated by Fig. 4, the bottom of the arms 22 rests on the bottom of the channel 13 and prevents tilting of the back 17 forwardly.

When the back 17 is swung backwardly, the front ends of the arms 22 engage with the underside of the flanges 14, and thus limit the amount of inclination of the back 20 17 (see Fig. 3).

The upper edge of the channel 19 is bent at right angles, as indicated at 23, and the upper edge of the latch 20 is likewise formed, as indicated at 24.

This construction of the top of the channel 19 and the top of the latch 20 provides a horizontal chamber, closed on three sides, in which a leaf-spring 25 is mounted (see Fig. 2).

The purpose of the spring 25 is to press the latch 20 downwardly so that its lower edge will at all times be in engagement with the bottom of the channel 13.

Mounted on the channel member 19, intermediate the ends thereof, is a bracket 26.

The bracket may be constructed from sheet-metal, bent to the form illustrated in Fig. 12.

This bracket projects through an aperture 27 formed in the latch 20, and an opening 40 28 formed in a follower plate 29.

The follower plate 29 has its lower portion offset, as indicated at 30, so that the bottom of this plate will be spaced rearwardly of the latch 20.

The lower portion of the plate 29 is formed with lateral projections 31, beneath which are formed inwardly extending slots 32.

The lower edge of the plate 29 is provided with a slot 33 through which the rod 16 passes. The latch 20 has a longer slot as indicated at 34. The purpose of the latter slot is to permit vertical movement of the latch.

On the other hand, as there is no vertical movement of the channel member 19 or the 55 foot 21, these parts are respectively provided with apertures 35 and 36, through which the rod passes.

The projections 31 of the plate 29 are disposed over the flanges 14, with the inner edges of the flanges disposed in the slots 32. In the normal or vertical position of the back shown in Fig. 4, projections 31 lie in notches 19b with their upper edges abutting the shoulders 19c and the lower edges abutting the flanges 13 of the tray channel 13.

The end of the bracket 26 has fixed thereon by means of a screw 37 and a U-shaped cap 41 (see Fig. 5), the upper end of a leaf-spring 38.

The spring 38 extends downwardly and 70 bears against the offset portion 30 of the plate 29.

As the plate is loosely mounted on the bracket, the pressure of the spring against the plate forces the upper edge of the plate 75 against the latch 20 and the lower end thereof toward the flanges 19a of channel 19.

When the back 17 is inclined, as shown in Fig. 3, the plate 29 will be disposed at an angle to the latch 20, and when the back is in vertical position, the plate is disposed substantially parallel to the latch.

The latch 20, adjacent to the offset portion 30 of the plate 29, is provided with a pair of spaced protuberances 39. These protuberances are inclined downwardly and outwardly, and serve as means for controlling movements of the plate.

The construction is such that the back 17 can be readily shifted to any desired position in the tray.

If only a few cards or sheets A are in the tray, then the back can be disposed adjacent to the end 2.

As the number of the cards or sheets is increased, the back can be moved rearwardly.

When the tray is not in use the back 17 can be in the vertical position shown by Fig. 4, and when the device is in use the back can be in the inclined position shown by Fig. 3.

For changing the back from the inclined position shown in Fig. 3 to the vertical position shown in Fig. 4, it is only necessary to push the top of the back forwardly. This action will shift the relative position of the plate 29 to the latch 20 from that shown in Fig. 3 to that shown in Fig. 4 due to the fact that the flanges 14 of tray channel 13 are engaged in notches 32 of plate 29. When projections 31 have their upper edges aligned with shoulders 19c of the channel flanges 19a of the back channel, the spring 38 will force them beneath the shoulders, thus latching the back in vertical position. The plate 29 thus constitutes a back-tilting control latch.

However, should it be desired to change the back from the vertical position shown in Fig. 4 to the inclined position shown in Fig. 3 then the horizontal edge 24 of the latch is grasped by the fingers, with the thumb resting over the top of the back 17, and the latch moved upwardly. This action will raise the bottom of the latch from its engagement with the serrated portion of the channel 13. The inclined portions 39 of the latch will engage with the face of the plate 29 immediately above the offset portion 30 thereof, and throw the plate outwardly thus disen-

gaging projections 31 from shoulders 19c and freeing the plate 29 for sliding movement. In this way the parts of the device which have been locked will be released, and when 5 backward pressure is exerted against the top of back 17 it will readily swing rearwardly to the position illustrated by Fig. 3.

On the other hand, should it be desired to shift the position of the back to increase or 10 decrease the distance between it and the ends of the tray, the horizontal edge 24 of the latch is grasped in the manner heretofore described, so as to release the parts locked in the channel 13. The back can then be slid 15 either forwardly or rearwardly as the bottom of the latch will have been raised above the protuberances 15. When the desired position has been reached, the latch can then be released and its lower edge will engage with the contiguous protuberance, with the other 20 parts occupying the positions illustrated.

The invention set forth herein, is of course, susceptible of various modifications and adaptations.

25 The invention claimed is:—

1. In a posting tray, the combination with a bottom having a flanged channel extending the length thereof, said channel having a serrated surface, of a back having a foot 30 portion connected thereto and disposed in the channel, and a substantially vertically movable latch carried by the back and engaging said serrations in the channel for locking the back in an inclined position 35 therein.

2. In a posting tray, the combination with a bottom having a flanged channel, said channel having a serrated surface, of a back, a member associated with the back having a 40 portion engaging the flanges thereof, to guide said back in its movement along said channel, and a substantially vertically movable latch for engaging said serrations and locking the back relative to the channel.

45 3. In a posting tray, the combination with a bottom having a flanged channel, of a back having a portion associated therewith and disposed in said channel, and adapted to be slidably retained thereby but to allow tilting 50 of the back from a vertical position to an inclined position, and a substantially vertically movable latch carried by the back and engaging with the channel for locking the back against sliding when in either of 55 said positions.

60 4. In a posting tray, a bottom having a channel extending longitudinally thereof, serrations in the bottom of said channel, a back, a guide member attached to said back and engaging with said channel to guide and support the back when it is being moved, and a substantially vertically movable latch member connected to said back and engaging 65 with said serrations.

65 5. In a posting tray, a bottom having a

channel extending longitudinally thereof, serrations in the bottom of said channel, a back, a guide member attached to said back and engaging with said channel to guide and support the back when it is being moved, a 70 supporting member for said back in the rear of the same, a substantially vertically movable latch member associated with said supporting member and terminating just short of the upper end of said supporting member, 75 and a spring between the latch member and the supporting member to keep the latch member normally in contact with the serrations.

6. In a posting tray, a bottom having a 80 channel extending longitudinally thereof and provided with flanges at its sides, a back having a foot slideable and tiltable in the channel, a follower plate having engagement with the channel whereby it is slideable therein but held against vertical movement with relation thereto and having slideable and pivotal engagement with the back, the back and follower plate being provided with elements coacting in one position of the back to prevent 90 tilting movement of the back, and a member carried by the back and shiftable thereon, said member having coaction with the follower plate to shift it about the pivot thereof as it is moved in one direction to 95 thereby disengage the said plate and said portions of the back to permit the back to be tilted.

7. In a posting tray, a bottom having a 100 channel extending longitudinally thereof, a back, a support and guide member attached to said back and slidably engaged in the channel, said support and guide member permitting tilting of the back, a follower member pivotally and slidably secured to the back 105 and slidably engaged with the channel, said follower member being movable about the pivotal connection thereof with the back from a position where it has engagement with the back preventing tilting of either 110 to a position where it clears the back to permit tilting thereof, and means for moving the follower member to the last-named position.

8. In a posting tray, a bottom having a 115 channel extending longitudinally thereof, a back, a support and guide member attached to said back and slidably engaged in the channel, said support and guide member permitting tilting of the back, a follower member pivotally and slidably secured to the back and slidably engaged with the channel, said follower member being movable about the pivotal connection thereof with the back 120 from a position where it has engagement with the back preventing tilting of either to a position where it clears the back to permit tilting thereof, means for moving the follower member to the last-named position, 125 130

and a spring normally maintaining the follower member in the first-named position.

9. In a posting tray, a bottom having a channel provided with a flange, a back, a support and guide member attached to said back and slidably engaged in the channel, a follower member having a notch receiving the flange of the channel, said follower member being pivotally and slidably secured to the back, a shoulder upon the back beneath which a portion of the follower member lies when the back is in vertical position, a spring normally maintaining the follower member beneath said shoulder, and means for shifting the follower member to disengage it from the shoulders and to thereby permit the follower member to slide with relation to the back and the back to be tilted.

10. In a posting tray, a bottom, a back 20 slideable over the bottom, serrations on the bottom, a latch coacting with said serrations to hold the back in adjusted positions, a member associated with the back and having engagement therewith and with said bottom normally preventing tilting of the back, and means upon the latch cooperating with said member to release said engagement when the latch is shifted to disengage it from said serrations.

30 PHILIP BERGMANN.
